VALVE MECHANISM FOR ROCK DRILLS

George H. Fuehrer, Easton, Pa., assignor to Ingersoll-Rand Company, Jersey City, N. J., a corporation of New Jersey

Application January 8, 1932, Serial No. 585,514

2 Claims. (Cl. 121—20)

This invention relates to fluid actuated rock drills, and more particularly to a valve mechanism for effecting the distribution of the pressure fluid to the percussive element of the drill.

5 One object of the invention is to effect a rapid distribution of pressure fluid to the piston chamber of the drill for actuating the piston.

Another object of the invention is to effect a positive action of the distributing valve, and still 10 another object is to accelerate or decelerate the action of the distributing valve at will.

Other objects will be in part obvious and in part pointed out hereinafter.

In the drawing accompanying this specification 15 and in which similar reference characters refer to similar parts,

Figure 1 is a sectional elevation of a rock drill equipped with valve mechanism constructed in accordance with the practice of the invention,

20 and

Figure 2 is a transverse view taken through Figure 1 on the line 2—2 looking in the direction indicated by the arrows.

Referring more particularly to the drawing, 25 A designates, in general, a rock drill comprising a cylinder B having a piston chamber C to accommodate a reciprocating hammer piston D. The cylinder B is provided with the usual front and back heads E and F, respectively, which may be 30 secured to the cylinder in any well known manner.

A closure is provided for the front end of the piston chamber C in the form of a front cylinder washer G which extends partly into the cylinder 35 B and the front head E and has a bore H through which extends slidably an extension J of the piston D. The extension J is provided with a series of flutes K to interlock slidably with introverted ribs L of a chuck member O arranged within the 40 front head E. In the front head E and forwardly of the chuck member O, wherewith it may be suitably interlocked, is a second chuck member P having a bore Q for the reception of a working implement, such as a drill steel R against which the 45 hammer piston D strikes.

In the rear end of the cylinder B is an enlarged bore S to accommodate a back cylinder washer T which acts as a closure for the rear end of the piston chamber C. The back cylinder washer T 50 also serves as a seat for a ratchet ring U arranged in the back head F.

Extending through the back cylinder washer T is a rifle bar V wherewith the piston D is slidably interlocked in a well known manner. The rifle 55 bar V carries the usual head W which lies within

the ratchet ring U and carries pawls X for engagement with teeth Y on the ratchet ring U to rotate the drill steel R, the piston D and the chuck members O and P.

In accordance with the present invention the 5 valve mechanism, employed for effecting the distribution of pressure fluid to the ends of the piston chamber C, comprises a valve chest Z which may extend longitudinally of the cylinder B and of which it may form a part. Within the valve chest 10 Z is a bore which extends from one end of the valve chest to the other to serve as a distributing valve chamber b for the accommodation of a distributing valve c.

Intermediate the ends of the valve chest Z is a 15 supply connection d through which pressure fluid may be admitted into an enlarged recess e in the valve chamber b and being located adjacent the supply connection d.

Closures are provided for the front and rear 20 ends of the valve chamber b in the form of plates f and g, respectively, and said plates are bored for the reception of a bolt h which extends coaxially through the valve c and is provided with a nut j whereby the plates f and g may be clamped fixedly 25 in position.

Leading from the valve chamber b at a point forwardly of the enlarged portion e and opening into the front end of the piston chamber C is a front inlet passage k through which pressure fluid 30 flows to drive the piston D rearwardly, and from a point rearwardly of the enlarged portion e of the valve chamber leads a rear inlet passage o which opens into the rear end of the piston chamber C to admit pressure fluid thereinto for driving the piston D forwardly on its working stroke.

The valve chest is further provided with front and rear exhaust ports p and q, respectively, and said exhaust ports are arranged between the inlet 35 passages and the ends of the valve chamber b.

The front and rear ends of the valve chamber b constitute pressure chambers r and s respectively. Each pressure chamber has a main exhaust port t which is so located that it will be 40 uncovered by the adjacent end of the valve c, preferably immediately before the end of the stroke of the valve. Between the exhaust ports t and the ends of the valve chamber b are compression relief ports u located a slight distance 45 from the ends of the valve chamber to provide an avenue of escape for some of the air in the pressure chambers and thus prevent the formation of sufficient compression to retard the action 50 of the valve before the valve has reached a posi- 55

tion to communicate the ends of the cylinder with pressure fluid supply.

In order to assure a nicely timed, rapid and positive action of the valve *c*, the rock drill is provided with additional valve mechanism designated, in general, by *v* to control the flow of pressure fluid to the pressure chambers *r* and *s* for actuating the valve *c*. For the sake of convenience of illustration the valve mechanism *v* is arranged at the rear end of the valve chest *Z*. It comprises a valve chest *w* which seats upon the plate *g* and is bored to accommodate the bolt *h* which serves to secure the valve chest *w*, as well as the plates *f* and *g*, in position. The valve chest *w* is suitably recessed to form therein a valve chamber *x* for the accommodation of a control valve *y*, as for instance of the oscillatory plate type, which rocks on its transverse median line *z* and has a pair of opposed wings 2 and 3 on opposite sides of the transverse median line *z*. The valve *y* has a bore 4 arranged coaxially in the valve to receive the bolt *h* which extends therethrough to hold the valve against lateral movement in the valve chamber *x*. Preferably the valve *y* is provided in its periphery and on the transverse median line *z* with notches 5 to engage pins 6 seated in the valve chest *w* for holding the valve *y* against rotary movement in the valve chamber. The pressure fluid distributed by the valve *y* is conveyed into the pressure chamber *s* through an inlet passage 7 in the plate *g* to act against an actuating surface 8 on the end of the valve *c* lying in the pressure chamber *s*, said passage 7 being located beneath the wing 2 of the valve *y* whereby it is controlled. Similarly, in the plate *g* is a front inlet passage 9 which is controlled by the wing 3 of the valve *y* and extends forwardly through the bolt *h* and opens into the pressure chamber *r*. The pressure fluid distributed by the valve *y* is conveyed to the valve chamber *x* through a supply passage 10 communicating at one end with the enlarged portion *e* of the valve chamber *b* and extending through the valve chest *Z*, the plate *g* and the valve chest *w* and opening into the valve chamber *x*. A portion of the passage 10, as for instance the portion 11 lying in the plate *g* may be somewhat enlarged, and a needle valve 12 threaded into the valve chest *w* extends through the enlarged portion 11 into the adjacent portion of the passage 10 lying in the valve chest *Z* to control the flow of pressure fluid through the passage 10 into the valve chamber *x*. The needle valve 12 may be provided with a suitable lock nut 13 to seat against the valve chest *w* for holding the needle valve 12 securely in position.

The valve *c*, selected for illustrative purposes, comprises front and rear end heads 14 and 15 and intermediate flanges 16 and 17. Between the flanges 16 and 17 is an annular groove 18 through which pressure fluid may flow to the inlet passages *k* and *o*. The head 14 and the flange 16 are separated by an annular groove 19 which, in one limiting position of the valve *c*, establishes communication between the inlet passage *k* and the exhaust port *p*. A groove 20, similar to the groove 19, is formed between the flange 17 and the head 15 to afford communication between the rear inlet passage *o* and the exhaust port *q*.

The operation of the device is as follows: With the valve *c* in the rearmost position and the wing 2 of the valve *y* raised as illustrated, pressure fluid flows from the enlarged portion *e* through the

annular groove 18 and the rear inlet passage *o* to the back end of the piston chamber *C* to drive the piston *D* forwardly on its working stroke. At the same time pressure fluid will flow from the valve chamber *x* through the inlet passage 7 into the pressure chamber *s* to act against the actuating surface 8 and will drive the valve *c* forwardly.

After the head 14 of the valve *c* covers the exhaust port *t* the air in the pressure chamber *r* will be expelled to the atmosphere through the port *u*, instead of being compressed, so that the valve *c* may quickly complete its forward stroke and establish communication between the enlarged portion *e* and the inlet passage *k*. When the valve *c* reaches this position pressure fluid will flow into the front end of the piston chamber *C* and will drive the piston *D* rearwardly.

As the valve *c* nears the foremost limiting position in the valve chamber *b* the head 15 uncovers the exhaust port *t* to permit the pressure fluid to exhaust from the pressure chamber *s*. Upon the exhaust of pressure fluid from the pressure chamber *s* the air flowing over the raised wing 2 of the valve *y* will tip the valve *y* to seat the wing 2 upon the plate *g* and to raise the wing 3 of the valve *y*. With the valve *y* in the new position pressure fluid flows over the wing 3 and through the passage 9 into the pressure chamber *r* to return the valve *c* to its initial position so that pressure fluid will again flow from the enlarged portion *e* of the valve chamber into the rear end of the piston chamber *C*.

By suitably adjusting the needle valve 12 the volume of pressure fluid flowing to the valve chamber *x* may be conveniently controlled. If the nature of the rock being drilled is such as to require a reduction in the speed of the hammer piston *D* the needle valve 12 may be adjusted to reduce the flow area of the passage 10. In consequence of this reduction the time required for charging the pressure chambers *r* and *s* will be somewhat lengthened and the action of the valves *y* and *c* will therefore be retarded. On the other hand, should the material being drilled be of such a nature as to require blows delivered in rapid succession to the drill steel *R* the needle valve 12 may be adjusted to increase the flow of pressure fluid to the valve chamber. With an ample supply of pressure fluid flowing to the valve chamber *x* the action of the valve *y* and, therefore, of the valve *c* will be increased with a resulting increase in the speed of the piston *D*.

I claim:

1. In a fluid actuated rock drill, the combination of a cylinder having a piston chamber and a piston therein, a valve chest having distributing and control valve chambers, a distributing valve in the distributing valve chamber to control the distribution of pressure fluid into the piston chamber, a control valve in the control valve chamber, opposed pressure chambers in the distributing valve chamber, inlet passages controlled by the control valve conveying pressure fluid from the control valve chamber to the pressure chambers for actuating the distributing valve and conveying compression from the pressure chambers to the control valve chamber for actuating the control valve, and free exhaust ports for the pressure chambers and being controlled by the distributing valve.

2. In a fluid actuated rock drill, the combination of a cylinder having a piston chamber and a piston therein, a valve chest having distributing

and control valve chambers, a distributing valve in the distributing valve chamber to control the distribution of pressure fluid into the piston chamber, a control valve in the control valve chamber, opposed pressure chambers in the distributing valve chamber, inlet passages controlled by the control valve conveying pressure fluid from the control valve chamber to the pressure chambers for actuating the distributing valve and

conveying compression from the pressure chambers to the control valve chamber for actuating the control valve, free exhaust ports for the pressure chambers and being controlled by the distributing valve, a supply passage for the control valve chamber, and a needle valve for controlling the supply passage.

GEORGE H. FUEHRER.
